SEAL HANGER

Frederick D. Moyer and Jack L. Scholbe, Chicago,
Ill., assignors to Chicago Bridge & Iron Com-
pany, a corporation of Illinois

Application February 2, 1950, Serial No. 142,020

2 Claims. (Cl. 220—26)

1

This invention relates to a seal hanger for sup-
porting a seal in a floating roof tank.

In floating roof tanks, a roof is constructed to
float on the liquid stored in the tank with the
roof having a relatively small space around its
periphery separating it from the walls of the
tank. An often used sealing member is con-
structed to slidably engage the walls of the tank
with the sealing member being supported by
means attached to the floating roof so that the
sealing member slides on the tank walls with any
rise or fall of the floating roof. Previous seal
hangers, such as shown in the application of
Wilber, Serial No. 637,016, filed December 22, 1945,
have been found faulty in continued use in that
they have become fouled with dirt and grit and
have failed in operation. This invention presents
a seal hanger which obviates the difficulties here-
tofore attendant with such supports for a seal in
a floating roof tank.

An embodiment of this invention is illustrated
in the accompanying drawing, in which

Fig. 1 is a plan view of a seal hanger of this in-
vention as installed on a floating roof tank;

Fig. 2 is a sectional view taken substantially
along line 2—2 in Fig. 1;

Fig. 3 is a sectional view taken substantially
along line 3—3 in Fig. 2; and

Fig. 4 is a vertical section showing fragmen-
tarily a portion of the tank wall and floating roof
with a seal hanger in operative position thereon.

As illustrated in Figs. 1 and 4 a floating roof 10
spaced from the side wall 11 is adapted to float on
the liquid 12 in the tank. A sealing member 13,
in the form of a metallic shoe comprising a flat
sheet of material having flexures 14 therein,
is formed to be pressed against the side wall 11 of
the tank and an impregnated flexible fabric 15
seals the space between the sealing member 13
and the floating roof 10. In order to effectively
seal the space between the floating roof 10 and
the side wall 11 of the tank the sealing member
13 must be pressed against the wall 11 of the tank
with sufficient force to effect a seal against the
wall. A spreading bar 16 is attached at spaced
points (not shown) to the sealing member 13 and
is forced outwardly against the shell of the tank
by the seal hanger 20 hereinafter described.

The seal hanger 20 is supported on the top 21
of a floating roof 10. A plate 22 is adjustably
held in a position above the top of the floating
roof 21 by three posts 23 having a pair of nuts 24
threaded on each post and positioned both above
and below the plate 22. The top 21 of the float-
ing roof 10 may not always be level so that the

2

three posts 23 with the associated nuts 24 on
either side of the plate 22 may be adjusted to
place the plate 22 in a horizontal position.

Mounted on the plate 22 is a U-shaped support
25 having the base 26 of the U resting against
the plate 22. A bolt 27 extends through both the
plate 22 and the base 26 of the support 25 and
has an expansion washer 28 positioned on the
lower side of the plate 22 to hold the support 25
and plate 22 in frictional engagement. In this
manner the support 25 is free to rotate about a
substantially vertical axis passing through the
center of the bolt 27.

The main portion of the seal hanger comprises
15 a plate bent into the shape of a channel member
30 having an open bottom 31 and welded or other-
wise fastened to the support 25 at one end. End
plates 32 are welded in the ends of the inverted
U-shaped channel member 30 and have an open-
ing 33 therein for admitting the seal support
member 40. A roller 34 is mounted on the inner
end of the channel member 30 so that the axis
35 of the roller is positioned beyond the end of
the channel member and is supported by a bracket
25 36 welded or otherwise fastened to the top of the
member 30. A similar roller 37 is supported by a
bracket 38 attached to the outer end of the mem-
ber 30 adjacent the support 25. The rollers sup-
port and help guide the seal support member 40
as hereinafter described.

The sealing member 13 is pressed against the
side walls of the tank 11 by the action of the
seal support member 40 and is also supported
by said member. The seal support member 40
35 may be a tubular pipe telescoped within the chan-
nel member 30 through the apertures 33 in the
end plates 32 and rolling on the rollers 34 and
37. The seal support member 40 is provided with
a pair of detents 41 against which a compression
40 spring 42 bears. The spring 42 also bears against
the inner end plate 32 to force the seal support
member 40 outwardly from the channel member
30 toward the side wall 11 of the tank. The outer
end 43 of the member 40 is flattened and has a
threaded aperture 44 therein. The flattened end
45 extends through a slot 45 in the spreading bar
16 and is engaged by the threads of a bolt 46
loosely extending through apertures in the legs
of the spreader bar 16. A spring 47 bears against
the lower side of the spreader bar 16 and the
head of the bolt 46 for the purpose of distributing
the load of the sealing member 13 evenly among
all the seal hangers employed in one floating roof
tank.

As the weight of the sealing member 13 is

placed on the seal support member 40 the member 40 bears downwardly against the front or outer roller 37 and upwardly against the inner roller 34, while the compression spring 42 exerts the necessary outward force on the member 40 to hold the sealing member 13 in close contact with the wall 11 of the tank. The floating roof 10 may shift its position within the walls of the tank so that more space between the roof and side walls may at a given time be present on one side of the tank than is present on the other side of the tank. The compression spring 42 has the tendency to return the floating roof 10 to the center of the tank and regardless of the positioning of the floating roof 10 within the tank, has sufficient force to press the sealing member 13 against the side walls. Should the floating roof 10 rotate slightly within the tank the seal hanger will pivot about its support and continue to press the sealing member 13 against the side walls. Usually a means is provided to keep the roof from rotating within the tank and may take the form of a vertically extending track running in a corresponding groove associated with the roof. Under normal conditions of use the seal hanger is directed radially against the side walls of the tank and will normally assume that position.

The seal hanger is usually mounted on the roof as a unit and then the sealing member 13 fastened thereto. Before installing the seal hanger on the floating roof, the seal support member 40 is pulled against the spring 42 until openings 43 appear outside the channel member 30 and a rod (not shown) is inserted in the openings 48 to bear against the end of the channel member to "cock" the seal hanger. After the hanger is installed and the flat end 43 is attached to the spreader member 16, the rod is removed and the seal hanger allowed to press the member 13 against the side wall of the tank.

The foregoing detailed description is given for clearness of understanding only and no unnecessary limitations should be understood therefrom but the invention should be construed broadly within the spirit and scope of the appended 45 claims.

We claim:

1. A seal hanger for a floating roof tank comprising, an upwardly flat base adapted to be attached to the roof, a support mounted on the base for rotational movement about a substantially vertical axis, an elongated channel member having an open bottom and mounted on the support, said support having a U-shape with the base of the U riding on the flat base and the upper ends of the U welded to said channel member, a seal support telescoped into said channel member and spring means within the channel member urging the seal support outwardly from the channel member.
- 5 2. In a floating roof tank, a hanger means to be secured to the upper exposed side of the floating roof for supporting a sealing member against the shell of the tank, comprising, a substantially horizontal pipe pivotally attached to and supporting the sealing member, a downwardly open channel member positioned over the pipe and having end plates with openings about the pipe admitting the pipe longitudinally of the channel member, a roller secured at each end of the channel member and having spaced parallel side bearing plates with the inner roller over the pipe and the outer roller under the pipe to provide rolling support for the pipe, and a pivotal support for the channel member including a pedestal and an upright U-shaped bracket pivoted at the base of the U to the pedestal and secured to the channel member at the free ends of the legs, said channel member and rollers being downwardly open whereby dirt, grit, etc. may fall from the hanger
- 10 30 35 to the roof.

FREDERICK D. MOYER.
